LOUIS ILLMER, JR., OF READING, PENNSYLVANIA, ASSIGNOR TO ILLMER GAS ENGINE COMPANY, A CORPORATION OF DELAWARE.

GAS-ENGINE.

1,089,132.

Specification of Letters Patent. Patented Mar. 3, 1914.

Application filed January 21, 1910. Serial No. 532,218.

To all whom it may concern:

Be it known that I, LOUIS ILLMER, Jr., of Reading, Berks county, State of Pennsylvania, have invented certain new and useful 5 Improvements in Gas-Engines, of which the following is a full, clear, and exact specification, such as will enable others skilled in the art to which it appertains to make and use the same.

10 My invention relates to a two cycle double acting gas engine, especially applicable to the upright marine type.

An important feature of this invention is the peculiar organization of parts by 15 which the engine may be reversed.

Another important feature is the construction and arrangement of the pump, by which explosive charges and scavenging air are introduced into the working chamber 20 and which pump is so combined with the other elements that it contributes to and follows the reversing operation. By thus combining these elements I am able to accomplish reversal by throwing over a lever, 25 so arranged that the other elements follow with such operation as may be necessary to bring about the reversal.

In the drawing: Figure 1 is an elevation of the engine, showing the starting valve in 30 section. Fig. 2 is a side elevation of the engine at the pump side thereof. Fig. 3 is a vertical cross-section through the pump and working chambers. Fig. 4 is a cross-section through the starting check valve.

35 10 designates the base of the engine; 11 the frame; 12 the working cylinder and 14 the pump cylinder. In the power cylinder 12 is arranged a double acting piston 15 on the rod 16, one end of which projects through 40 the cylinder and is attached to a cross-head 17 running on a guide 18 and connected by a rod 19 with a crank 20. In each end of the cylinder 12 is arranged an annular inlet valve 21 while the exhaust ports 22 are 45 located at the middle of the cylinder and opened and closed by the piston, as usual.

The inlet valves are mechanically operated from an eccentric 23 on the crank shaft 20 driving an eccentric rod 24. This rod is 50 articulated to an eccentric rocker arm 25 mounted on a stud 26 carried by the frame. The arm 25 drives a reach rod 27 (broken away in Fig. 1) and said rod 27 in turn drives a rocker 28 mounted on a stud 29 55 carried by the cylinder 12. This rocker is

connected by links 30 with the valve operating linkage 31, which may be of any desired type, but is preferably operated by means of the double toggle shown in the drawings. The inlet valve eccentric is set 60 so that its phase position coincides approximately with that of the power piston movements.

Within the pump cylinder 14 is the piston 32, actuated by a rod 33 which is joined to 65 a cross-head 34 running in a guide 35. The cross-head 34 is joined to a connecting rod 36 which is connected to a block 37. This block slides in a rocker quadrant 38 which is pivoted on a stud 39 and receives its motion from two links 40 articulated to the connecting rod 19. The mechanism shown normally drives the pump so as to lead in phase position approximately 90 degrees with respect to the power piston movements. 75

The connecting rod 36 and the block 37 are adapted to be shifted on the quadrant 38 when the engine is reversed, so as to cause the pump piston to lag in phase, approximately 90 degrees with respect to the power piston movements while the engine is coming to a rest, as will hereinafter fully appear. This shifting of the connecting rod 36 may be brought about in any desired manner. I have shown a lever 41 intermediately fulcrumed and connected at its lower end with the rod 36 by a link 42, the upper end having a toothed quadrant 43 engaged with a worm 44 rotatably mounted and operated manually by a wheel 45. By 80 rotating this wheel 45 the lever 41 may be actuated to throw over the rod 36 while the engine is running.

46 designates the casing of the starting valve for timing the flow of the compressed 85 starting air into the power cylinder, and 47 designates the valve proper. The stem of the valve 47 is pivoted to the intermediate portion of a floating lever 49, one end of which lever is articulated to a rod 50 and 100 the other end to an intermediately fulcrumed lever 51. The rod 50 is pivoted to the rocker arm 25 and the rod 51 is joined to the pump cross-head 34 by means of a link 52. It will be seen therefore that the 105 starting valve is actuated by the combined motions of the eccentric 23 and pump rod connections, so that, in this manner, I secure the proper timing of the starting valve, as will be later set forth. 110

53 designates the entrance for a supply of gas, controlled by a throttle valve 54 which allows the gas to enter the chamber 55 of the pump. Said valve is adapted to be actuated by hand, or automatically by a governor (not shown).

56 designates the air supply chamber of the pump which communicates with the atmosphere through a perforated wall 57.

10 The air and gas movements are under control of valves 58 which will be described later.

At each end of the pump are U-shaped connections 59 which communicate with the 15 pump and with the passages 60 leading respectively to the inlet valves 21 of the working cylinder 12. Said passages are provided with reticulated walls 61 and baffles 62 to insure proper mixing of the 20 air and gas, fully set forth hereinafter. Normally the pump is driven to lead the power piston movements so that when one of the inlet valves 21 opens, the pump piston is moving toward that valve and forcing 25 the air and gas into the power cylinder. The starting valve is so arranged that through its pipe connections 63 it will normally throw compressed air into the ends 30 of the power cylinder at the time that the piston is moving from the same.

66 designates check valves which open into the cylinder 12 to admit air from the pipe connections 63. Compressed air is supplied to the starting valve through a connection 64 controlled by a valve 65 from a tank (not shown).

The engine is provided with the usual ignition devices (not shown) and serves to compress, ignite and expand the charge in 40 the manner usual in this class of engine. Assuming that the parts are in the adjustment shown in Figs. 1 and 3 and that the engine is running in the direction indicated by arrows in Fig. 3, to reverse the engine, 45 the hand wheel 45 is operated so as to throw the pump connecting rod 36 over to the other side of the rocker 38. This will result in simultaneously changing the action of the pump piston and of the starting 50 valve. The pump piston will thereby be caused to reverse its motion, and, until such time as the engine begins to reverse, the starting valve will be shifted in phase so as to throw compressed air into the power 55 cylinder at or about mid-compression stroke. The piston 15 at this time will continue its downward motion under the force of the explosion above it, but the pump piston, moving upward, will, while the lower 60 inlet valve is open, tend to draw the charge back out of the lower end of the cylinder. The continued downward motion of the piston 15 will, when the inlet valve closes, compress the air and gas or the air alone in 65 the lower end of the power cylinder and

when the piston is at mid stroke compressed air will be admitted into the lower end of the cylinder until the pressure therein equalizes with the pressure of the compressed air supply at which time the compressed air supply will be cut off by the action of the check valves controlling the air supply into the cylinder. The still continued motion of the piston serves to further compress the air, and, on account of 70 piston leakage and the cooling effect on the cylinder walls, a portion of the energy of the highly compressed air will be dissipated so as to retard the motion of the engine. When the bottom dead center position of the piston is reached the inlet valve at the top of the cylinder will be opened, but by this time the pump piston will be moving downward and therefore will not force any charge into the top of the cylinder. 75

The piston then returns toward its upper position, the engine still running in its original direction as shown by the arrow at the crank shaft in Fig. 3, but at reduced speed. When the middle of the upward stroke is 80 reached, the starting valve, whose action has been changed by shifting the rod 36, will cause air to be thrown into the upper end of the cylinder against the uprising piston. The compressed air so admitted, finally 85 stops the upward motion of the piston and forces it downward, reversing the direction of rotation of the engine shaft 20. The engine shaft and its connected piston will then run in the reverse direction and this 90 reverse direction corresponds precisely with the reversed adjustment of the pump and starting valve, so that the starting valve now again throws air into the cylinder ends 95 at the times that the piston reaches the beginning of its expansion strokes and the engine, operating as an air engine, immediately accelerates its speed in the reverse direction. Meanwhile, the pump will be operating in synchronism with, but now leading 100 in phase with respect to the power piston movements, and, after a few revolutions, the pump will resume its normal operation and explosion within the working cylinder will again take place, driving the engine as before, but reversely to its former direction 105 of motion. After the reversal of the engine has been accomplished the igniting mechanism should be adjusted to give the spark 110 the proper lead with respect to the power 115 piston.

Of the check valves which control the starting air admission from the connections 63, one is shown in Fig. 3. There are two of these valves, one at each end of the working cylinder, and, as shown in section in Fig. 4, each is contained within a suitable housing 67 and normally closed by springs 68. When, therefore, the starting valves 120 throw air into either of the connections 63, 125 130

the corresponding valve 66 opens and remains open until the pressure in the cylinder equalizes the pressure in the connection 63, whereupon the check valve 66 closes. 5 After the engine is started, or, after it has been reversed, the compressed air may be cut off completely by closing the valve 65. This method of operation however is not absolutely essential, since, in normal operation, 10 the starting valve throws air into the connections 63 after the instant of explosion in the end of the cylinder to which the connection leads. At this time the pressure in the cylinder will be greater than that of the compressed air and hence the 15 valves 66 will not open.

The starting valve for timing the flow of compressed air into the power cylinder is shown in section in Fig. 1 and it comprises 20 a double piston valve, the sections of which are connected by a reduced portion or neck 69. The casing 46 has a central chamber 70 and end chambers 71. The chambers 71 communicate respectively with the connections 25 63. The chamber 70 communicates with the supply pipe 64. The reciprocation of the valve serves alternately to connect the middle chamber 70 with the end chambers 71 to supply compressed air alternately to the 30 pipes 63. The gearing which I have employed for driving this valve 47 and the connection of this gearing with both the eccentric 20 and the pump rod 36 enables me to give the valve the proper movements which 35 result in the above described operation of reversing the engine. By means of such mechanism the starting valve is made to shift in phase position by about 45 degrees with respect to the power piston movements.

40 The details of the pump and its method of operation will now be described: The gas inlet port 53 is controlled by the throttle 54 and connects with the gas chamber 55. The chamber 55 has two ports 73 communicating 45 with the seat housings of the valves 58. These housings also have ports 74 communicating with the air supply chamber 56 and ports 75 communicating with the ducts 59, and ports 76 communicating with the pump 50 cylinder 14. The valves 58 are mechanically operated in unison with the cycle of the engine through arms 77 fastened to their stems (see Fig. 1) and joined by links 78 with the links 30 of the inlet valve gear, the arrangement being such that the valves 58 alternately assume the two positions shown in Fig. 3, in one of which the air and gas supplies are shut off from the pump cylinder and the ports 75 and 76 communicate with 55 each other, and, in the other of which the ports 75 and 73 communicate with each other on one hand and the ports 74 and 76 communicate with each other on the other hand.

60 65 The operation of the pump valves from

the inlet valve eccentric forms an important feature of the present invention.

The U-shaped ducts 59 have each of them one leg communicating respectively with the ports 75, while the other legs of the 70 ducts communicate with the ports 79 in the heads of the pump cylinder 14. These ducts 59 communicate with the inlet passages 60 intermediate their ends at the sides adjacent the ports 79, thus dividing the ducts into two 75 sections, *i.e.* the section between the ports 79 and passages 60 (termed the air leg) and the section between the ports 75 and the passages 60 (termed the gas leg).

The operation of the pump is as follows: 80 Assuming the parts to be in the adjustment shown in Fig. 1, the downward motion of the piston 32 will cause air to be drawn into the top of the cylinder 14 through the ports 74 and 76. The upper inlet valve 21 being 85 closed, the downward motion of the piston 32 rarefies the air in the duct 59 and causes gas to be drawn through the ports 73 and 75 into the gas leg of the top duct 59. At the end of the stroke the top of the cylinder 90 14 is filled with air which extends through the air leg of the top duct 59 and through the connection 60 leading to the inlet valve, while the gas leg of the duct 59 extending between the port 75 and connection 60 is 95 filled with gas, the front or advance face of which lies either at or adjacent to the entrance of the connection 60. Upon return motion of the piston 32 the valves 58 reverse their position and the above described operations are repeated in the lower end of the pump. Meanwhile, the upper inlet valve 21 will have been opened and the working piston 15 will have overrun the exhaust ports 100 22 and opened the same to communication 195 with the upper end of the working cylinder 12. Thereupon, the upward motion of the pump piston causes a pressure to be developed in the upper end of the pump cylinder which is followed by currents in both 110 the air and gas legs of the upper duct toward the connection 60. This forces into the working cylinder the air lying in the connection 60, such air constituting a stratum which flows through the power cylinder to 115 120 scavenge and cool it. Continued flow of air in the air leg and of gas in the gas leg of the duct 59 causes the air and gas to meet at the entrance to the connection 60 and they are there mixed by the baffles 61 and 62, 120 forming the explosive mixtures which pass on into and through the connection 60, past the still open inlet valve 21 and into the cylinder 12 as the working charge. This stratum of explosive mixture thus formed 125 and introduced is followed by the remaining air flowing from the pump cylinder, which air flowing into the connection 60 pushes the explosive mixture into the cylinder 12 and itself lies in the connection 60. There- 130

upon the inlet valve 21 closes and the air in the connection 60 is in a position to be introduced into the cylinder as the scavenging blast at the next following period in the cycle when the piston is at the top of the engine cylinder. The piston 32 in returning brings about, in the lower end of the pump and in the lower end of the working chamber, operations similar to those just described.

It will therefore appear that by means of my invention involving the use of a single pump fitted only with two valves, I supply to the working chambers of a double acting engine alternate strata of scavenging air and explosive mixture which strata pass successively to the cylinder, the scavenging air blowing through the same to cleanse and cool it and the mixture stratum entering the cylinder as the working charge and followed by a second stratum of scavenging air which lies back of the inlet valve isolating it from the gas supply and preventing back explosions. If desired the discharge of the pump may be adjustably controlled by means of a suitable by-pass. As shown in the drawing, the cavities 80 are formed in the walls of the pump cylinder 14, adjacent to and communicating with the ports 76, and from these cavities 80, the ports 81 lead to pipe connections 82 outside of the cylinder (Fig. 1) and return to ports 83 communicating with the interior of the pump cylinder (Fig. 3). Numeral 84 designates the control valves in the pipe connections 82 by which the by-pass may be adjusted.

The organized operation of the engine may be traced as follows: To start the engine the air valve 65 should be open and the engine turned off center. Instantly air pressure will be supplied to one or the other end of the working cylinder 12 according to the position of the starting valve, causing the engine to turn over and to operate as an air motor. The engine thus operating, drives the piston 32 of the pump and the strata of air and gas are formed and admitted to the engine cylinder as above described. As soon as a working charge is entered into place in the working cylinder and compressed therein it will be exploded by the spark and from that time on the engine will take up its normal operation as an explosive engine. The starting air now becoming inoperative, by reason of the superior pressure of the exploding charges keeping closed the check valves 66. At this time it is preferable to close the valve 65, though, as I have before stated, this may be left open without detriment. To reverse the engine, the pump connecting rod 36 should be thrown over to the quadrant 38, thus reversing the action of the pump, rendering it for the time inoperative to throw

charges into the working cylinder. Simultaneously the starting valve 47 will be reversed and this will cause the engine to be first brought to rest and then turned backward, again operating as an air motor until the pump resumes its normal operation and throws the working charges into the cylinder, whereupon, the engine resumes its normal operation, but in a reverse direction.

What I claim is:—

1. In a reversing two-cycle internal combustion engine having a power cylinder, a pump normally discharging the motive fluid into the power cylinder, a pump piston operated to lead in phase position with respect to the power piston movements, means shifting the pump piston to lag in phase position whereby the pump ceases its discharge of motive fluid while the engine is coming to rest, and resumes its normal discharge functions immediately upon reversal of rotation.

2. A reversing internal combustion engine having a power cylinder and piston, a pump supplying the motive fluid to the power cylinder, a starting valve for timing the flow of starting air into the power cylinder, means shifting the phase position of the pump and the starting valve with respect to the power piston movements while running, whereby to cause the pump to cease its discharge of motive fluid and to cause the starting valve to throw compressed air against the power piston during its compression stroke while the engine is coming to rest.

3. A two-cycle internal combustion engine having a power cylinder and piston, a pump supplying the motive fluid to the power cylinder, a starting valve timing the flow of starting air into the power cylinder, means for driving the pump and the starting valve in synchronism and for shifting their phase positions with respect to the power piston movements while running, whereby to cause the pump to cease its discharge of motive fluid and to cause the starting valve to throw compressed air against the power piston during its compression stroke while the engine is coming to rest and to immediately start the engine in the reverse direction by throwing compressed air against said piston during its expansion stroke, after which the pump immediately resumes its normal charging functions.

4. In a two-cycle internal combustion engine having a power cylinder and piston, an inlet valve for the power cylinder, a pump normally discharging the motive fluid to the inlet valve, a pump piston operated to lead in phase position with respect to the power piston movements, a suction valve for the pump, a crank shaft, an eccentric mounted thereon, means operating both the

- inlet valve and the suction valve from said eccentric and means for shifting the pump piston to lag in phase position while running and to cease its normal discharge functions while coming to rest.
5. In a two-cycle internal combustion engine, a power cylinder, an inlet valve to the cylinder, a pump supplying the working charge to the cylinder, a suction valve for the pump, a crank shaft, an eccentric mounted thereon and means mechanically operating both the inlet valve and the suction valve from the eccentric.
6. In a two-cycle internal combustion engine, a power cylinder, an inlet valve for the cylinder, separate supplies of air and gaseous fuel, a suction valve for said supplies, a crank shaft, an eccentric on the crank shaft, and means mechanically operating both the inlet valve and the suction valve from the eccentric.
7. In a two-cycle internal combustion engine, a power cylinder, an inlet valve for the cylinder, a pump supplying the working charge to the inlet, a discharge valve for the pump, a crank shaft, an eccentric thereon, and means mechanically operating both the inlet valve and the discharge valve from the eccentric.
8. In a two-cycle internal combustion engine, a power cylinder and piston, an inlet valve for the cylinder, a crank shaft, an eccentric on the crank shaft and operating the inlet valve, a pump supplying the working charge to the power cylinder and so driven as to lead in phase position with respect to the power piston movements, a starting valve timing the flow of air into the power cylinder, and means for operating the starting valve by the combined motions of the eccentric and the pump piston movements.
9. In a two-cycle internal combustion engine having a power cylinder and piston, an inlet valve for the cylinder, a pump supplying the working charge to the power cylinder and so driven as to lead in phase position with respect to the power piston movements, a starting valve timing the flow of compressed air into the power cylinder, means operating the starting valve by the combined motions of the eccentric and the pump piston movements, and means for shifting the phase of the pump piston movements while running, to simultaneously shift the phase of the starting valve movements with relation to the power piston movements.
10. In a reversing two-cycle internal combustion engine, a power cylinder and piston, a pump normally discharging the motive fluid into the power cylinder, a starting valve normally timing the flow of starting air into the power cylinder during the expansion stroke, means for shifting the phase positions of both the pump and the starting valve movements with respect to the power piston movements, whereby to cause the pump to cease its discharge of motive fluid and to throw compressed air into said cylinder during the compression stroke.
11. In an internal combustion engine having a power cylinder and a piston, an inlet valve to the cylinder, a pump discharging to the power cylinder, a control valve for the pump, a crank shaft and a valve gear means in operative connection with the crank shaft for oscillating both the inlet valve and the control valve.
- In testimony whereof I have signed my name to this specification in the presence of two subscribing witnesses.
